(57) CLAIM

I claim the ornamental design for a container for cotton sticks, as shown and described.

DESCRIPTION

FIG. 1 is a perspective view of the container for cotton sticks;

FIG. 2 is a perspective front view of a container for cotton sticks of FIG. 1 with an open top portion;

FIG. 3 is a left side view of the container for cotton sticks, the right side being a mirror image;

FIG. 4 is a back view of the container for cotton sticks;

FIG. 5 is a top view of the container for cotton sticks; and,

FIG. 6 is a front view of the container for cotton sticks.
